[57] CLAIM

The ornamental design for a combination lipstick and lipliner dispenser, as shown and described.

DESCRIPTION

FIG. 1 is a right side elevational view of a combination lipstick and lip liner dispenser showing my new design with the caps removed for completeness of disclosure; the left side being a mirror image of the side shown;

FIG. 2 is a perspective view thereof, seen from the lipstick end;

FIG. 3 is a perspective view thereof, seen from the lip liner end;

FIG. 4 is a perspective view of the assembled article; and,

FIG. 5 is a side elevational view thereof, the side opposite being a mirror image of the side shown.
